Primary Examiner — Michael A Maharajh(74) *Attorney, Agent, or Firm* — Jeffer Mangels; Butler & Mitchell LLP; Brennan C. Swain, Esq.**CLAIM**

The ornamental design for a percussive massage device, as shown and described.

DESCRIPTION

FIG. 1 is a perspective view of a percussive massage device, showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines in the drawings are for the purposes of illustrating portions of the percussive massage device, which form no part of the claimed design.

1 Claim, 6 Drawing Sheets(56)
